Primary Examiner — Anhdao Doan*(74) Attorney, Agent, or Firm* — Banner & Witcoff, Ltd.**CLAIM**

The ornamental design for an ultrasonic diagnosis apparatus, as shown and described.

DESCRIPTION

FIG. 1 is a front, top and right side perspective view of a ultrasonic diagnosis apparatus, showing our new design; FIG. 2 is a rear, top and left side perspective view thereof; FIG. 3 is a front view thereof; FIG. 4 is a right side view thereof; FIG. 5 is a rear view thereof; FIG. 6 is a left side view thereof; FIG. 7 is a top view thereof; FIG. 8 is a bottom view thereof; FIG. 9 is an enlarged end view thereof, taken along the line 9-9 in FIG. 3, with its internal mechanisms omitted; and, FIG. 10 is an enlarged cross sectional view thereof, taken along the line 10-10 in FIG. 4. The broken lines in FIG. 3 are included to indicate the cutting plane of FIG. 9. The broken lines shown in FIGS. 9 and 10 are for environmental purposes only and form no part of the claimed design.
